(57) **CLAIM**

The ornamental design for a tonometer tip, as shown and described.

DESCRIPTION

FIG. 1 is a perspective view of the tonometer tip, showing my new design.

FIG. 2 is a first side elevational view thereof;

FIG. 3 is a cross-sectional view thereof taken along line 3-3 of FIG. 2;

FIG. 4 top plan view thereof; and,

FIG. 5 is a bottom plan view thereof.

The broken lines are included for the purpose of illustrating portions of the tonometer tip that form no part of the claimed design. The oblique line shadings in FIGS. 1, 2, and 4 are included to show transparent surfaces.
